(57) **CLAIM**

The ornamental design for a lighted dog vest as shown and described.

DESCRIPTION

FIG. 1 is a top, front right side view of the lighted dog vest; FIG. 2 is a front view thereof;

FIG. 3 is a back view thereof;

FIG. 4 is a left side view thereof;

FIG. 5 is a right view thereof;

FIG. 6 is a top view thereof;

FIG. 7 is a bottom side view thereof;

FIG. 8 is a perspective thereof with a dog drawn in broken lines for environmental purposes only;

FIG. 9 is a perspective view of the lighted dog vest, shown in an expanded configuration;

FIG. 10 is a front view thereof;

FIG. 11 is a back view thereof;

FIG. 12 is a left side thereof;

FIG. 13 is a right side thereof;

FIG. 14 is a top view thereof; and,

FIG. 15 is a bottom view thereof.

The broken lines on the lighted dog vest depict stitch lines and form no part of the claimed design. In FIG. 8, the broken lines showing a dog depict environment and form no part of the claimed design.

The claimed design shows a contrast of materials by using line shading in one area and stippling in another.
